UNITED STATES PATENT OFFICE.

GEORGE S. AXFORD, OF DETROIT, MICHIGAN.

REINFORCED BOX.

1,115,478.

Specification of Letters Patent.

Patented Nov. 3, 1914.

Application filed December 14, 1912. Serial No. 736,716.

To all whom it may concern:

Be it known that I, GEORGE S. AXFORD, a citizen of the United States, residing at Detroit, county of Wayne, State of Michigan, have invented a certain new and useful Improvement in Reinforced Boxes, and declare the following to be a full, clear, and exact description of the same, such as will enable others skilled in the art to which it pertains to make and use the same, reference being had to the accompanying drawings, which form a part of this specification.

This invention relates to boxes and has for its object a reinforced box which is better adapted to withstand rough usage than the boxes in common use.

I prefer to employ a box which has reinforcing timbers at the ends and which is wire wound. It is also provided with reinforcing angle strips on the inside. These, however, are features that are additional to my improvement which consists in providing reinforcing strips and angle plates which not only prevent the wearing and breaking of the box by abrasion, but also serve to connect the ends of the box with each other and to thereby stiffen and reinforce the sides of the box which are not constructed of as heavy material as the ends.

In the drawings:—Figure 1, is a perspective of the box with one side taken away. Fig. 2, is a perspective of the reinforcing strip. Fig. 3, is a perspective of the corner plate. Fig. 4, is a side elevation of a finished box.

The box is strongly constructed by using the end pieces, or boards, A and B, which are fastened perpendicularly to the bottom C and also supported in such position by the reinforcing timbers 1. At the tops of the ends A and B are located similar reinforcing timbers 2 and these are connected with the reinforcing timbers 1 by side reinforced timbers 3. The box is reinforced at the inside by the angle strips 4 and 5 which run along the meeting edges of the side members, end members and bottom.

I fasten to each corner by nails or otherwise the angle plate 6. These angle irons fold over the side reinforcing timbers 2 and overlap a portion of the reinforcing timbers 3. Over the upper edges of the sides fits a reinforcing strip 7, which is constructed as shown in Fig. 2. It is made of metal which is twice folded so as to form the three webs. At the ends the extensions 8 are cut

and are intended to lie on top of the reinforcing timbers 2, as shown in Fig. 1. These extensions 8 are at the ends nailed to the reinforcing timbers 2 by a large fastening member 9 and near the middle are secured by small fastening members 10 that pierce the angle plate 6 and fasten that also to the reinforcing timbers.

A similar reinforcing strip 7 is fitted over the side D which has been taken away from the illustration of Fig. 1. It will readily be understood that this forms a very strong and serviceable box. It is intended to be used especially with wire bound boxes, such as I have shown in Fig. 4, but I do not limit myself to such boxes alone, as my reinforcing construction can be used without the wire bound feature. This form of construction is especially adapted to grocery boxes, and not only makes a stronger box less liable to collapse, but also prevents the wearing of the edges from knocks and scraping.

What I claim is:—

1. A delivery box, having in combination, a bottom, two sides and two ends, and reinforcing timbers in the form of a parallelogram at each end which follow the edges of the ends, and a metallic strip folded over the top of the side to straddle the side and form a protecting strip on the inside of the side from end to end of the box and on the outside from one extreme end to the other extreme end, the said metal strip having extensions that represent the metal that would have to be cut off at the ends of the strip to allow the strip to fit into the inside of the box, the said extensions extending out perpendicularly from the strip to overlie the reinforcing timbers and the upper edges of the ends of the box adjacent the corners.

2. A delivery box, having in combination, a bottom, two sides and two ends, reinforcing timbers in the form of a parallelogram at each end which follow the edges of the ends, angle plates, one at each corner, each angle plate comprising two portions one of which overlies the top of the reinforcing parallelogram and the other of which overlies the side of the reinforcing parallelogram adjacent the corner, and a metallic strip folded over the top of the side to straddle the side and form a protecting strip on the inside of the side from end to end of the box and on the outside of the side from one extreme end to the other extreme end, the ends of the said metallic strip

overlying the top portions of the angle plate at its corners, the said metallic strip having extensions that represent the metal that would have to be cut off at the ends of the strip to allow the strip to fit into the inside of the box, the said extensions extended out perpendicularly from the strip to overlie portions of the top portions of the adjacent angle plates and also to overlie the reinforce-

ing timbers and the upper edges of the ends of the box adjacent the corners.

In testimony whereof, I sign this specification in the presence of two witnesses.

GEORGE S. AXFORD.
